[57] CLAIM

The ornamental design for a combined computer and
scale for preparing mixtures of paints, colors and lac-
quers, as shown and described.

DESCRIPTION

FIG. 1 is a front perspective view of a combined com-
puter and scale for preparing mixtures of paints, colors
and lacquers showing our new design;

FIG. 2 is a front elevational view thereof;

FIG. 3 is a rear elevational view thereof;

FIG. 4 is a top plan view thereof;

FIG. 5 is a left side elevational view thereof;

FIG. 6 is a right side elevational view thereof; and,

FIG. 7 is a bottom plan view thereof.

FIG. 1

FIG. 2

FIG. 3

FIG. 4

FIG. 5

FIG. 7
